UNITED STATES PATENT OFFICE.

EMIL WESTMAN, OF MINNEAPOLIS, MINNESOTA.

ELECTRIC IGNITER FOR EXPLOSIVE-ENGINES.

No. 922,987.

Specification of Letters Patent.

Patented May 25, 1909.

Application filed October 5, 1907. Serial No. 395,984.

To all whom it may concern:

Be it known that I, EMIL WESTMAN, a citizen of the United States, residing at Minneapolis, in the county of Hennepin and State of Minnesota, have invented certain new and useful Improvements in Electric Igniters for Explosive-Engines; and I do hereby declare the following to be a full, clear, and exact description of the invention, such as will enable others skilled in the art to which it appertains to make and use the same.

My invention has for its object to provide an improved electric igniter for explosive engines, and to this end it consists of the novel devices and combinations of devices hereinafter described and defined in the claims.

In the accompanying drawings which illustrate the invention, like characters indicate like parts throughout the several views.

Referring to the drawings, Figure 1 is a diagrammatic view, showing the improved sparking plug which constitutes a part of the invention, connected in a common circuit with a suitable timer, and with a battery or other continuing source of supply of the igniting current. Fig. 2 is a view chiefly in vertical section, but partly in side elevation, showing the improved sparking plug. Fig. 3 shows the improved sparking plug chiefly in front elevation, but with some parts sectioned and with some parts broken away; and Fig. 4 is a horizontal section 35 taken on the line $\alpha^4 \alpha^4$ of Fig. 2.

The parts which make up the so-called sparking plug and which are best illustrated in Figs. 2, 3 and 4, will first be described. This sparking plug preferably has a thin metal casing 1 of cylindrical form which, at its lower end, is secured to the outer end portion of a metal plug 2, the threaded end 3 of which is, as is usual, adapted to be screwed into a suitable seat in the head of the cylinder of the engine to which the igniter is applied. A cap 1^a of insulating material is preferably used to close the upper end of the casing 1. A metal bushing 4 is passed axially through the plug 2, and a suitable insulating sleeve 5 insulates the said bushing 4 from said plug. A bearing bracket 6 rests upon the out-turned upper flange of the insulating sleeve 5 and is rigidly secured to the plug 2 by a nut 7 on the upper end of 55 the bushing 4 which engages the foot portion of said bracket.

One of the electrodes 8 is preferably fixed and is secured to and has electrical connection with the plug 2. The other electrode 9, which is in the form of an arm, is carried by the lower end of a vertical rock shaft 10 that is extended axially through the bushing 4 and is provided at its upper end with an arm 11.

An electrode magnet 12 is supported by the bracket 6, and a co-operating armature 13 which, as shown, is in the form of a soft iron plate, is pivotally supported at its upper end to a portion 6^a of the bracket 6 which, as shown, overlies the magnet 12. At its lower end, the armature 13 is provided with a projecting arm 14 that is adapted to engage the headed end of the arm 11 of the rock shaft 10. A light spring 15, shown as connected to the bracket extension 6^a and the upper portion of the armature 13, normally holds the said armature in the position shown in Figs. 2 and 4, with its arm 14 a considerable distance from the head of the arm 11. The movement of the armature 13 away from the magnet 12 is, as shown, limited by stop nuts 16 on the outer end of a stud 17, which, as illustrated, is secured to the core 12^a of the magnet 12 and is passed through a suitable perforation 13^a in said armature. The two electrodes 8 and 9 are normally held in contact by a light coiled spring 18 which, as shown, is connected to a pin 19 on the bracket 6 and to a pin 20 that projects from the hub of the arm 11.

The magnet 12 and the electrodes 8 and 9 are connected in a common circuit with a timer 21 and with a battery or constant source of electrical energy 22 by wires 23 and the metallic parts of the sparking plug above described. The so-called timer, indicated as an entirety by the numeral 21 and just above noted, may be of any suitable construction, but must, of course, have parts that are arranged to open and close the 100 sparking circuit with a properly timed action in respect to the movement of the piston of the engine to which the igniter is applied. When the electric igniter is applied to a multi-cylinder engine, the so-called 105 timer would be of a form usually designated as a distributor.

The source of electrical energy 22, indicated in the drawings as a battery, may take various forms and might be a dynamo. It need not necessarily be one that supplies an absolutely uninterrupted current, but it is

essential to this invention that it be one that will supply an electrical current approximately through the interval of time that the igniting circuit is closed by the so-called timer. The important reason for this will appear a little later on.

As shown in the drawings, one of the circuit wires 23 is connected to a contact screw 24 that is supported by but insulated from 10 the upper end extension 6^a of the bracket 6. One terminal of the coil 12^b of the magnet 12 is connected to the contact screw 24, and the other terminal thereof is connected to the metallic bracket 6. One of the wires 23, 15 as shown, is directly connected to the metal plug 2. When the igniting circuit is closed, the current flows through the timer 21, battery 22, wires 23, contact screw 24, magnet coil 12^b, bracket 6, bushing 4, shaft 10, sparking electrodes 8—9 and metal plug 2.

Normally, the igniter circuit is closed at all points except through the timer 21. When the circuit is closed through the timer 21, the magnet 12 is energized and imparts 25 a quick movement to the armature 13 from the right toward the left with respect to Fig. 2. In this movement of the armature, it first acquires considerable momentum and then strikes the head of the arm 11 with a 30 sort of hammer blow which effects a very quick separation of the movable electrode 9 from the fixed electrode 8. An arc is established and a spark is produced, of course, by the separation of these two electrodes. The 35 separation of the two electrodes, however, breaks the circuit through the coil of the magnet 12, thereby deenergizing the said magnet and permitting the spring 15 to throw the armature to its normal position 40 and the spring 18 to move the electrode 9 back into contact with the electrode 8. These movements of the armature and movable electrode take place so rapidly that the 45 sparking circuit will be closed and broken several times between the electrodes, and thus produce a multiplicity of sparks during the interval of time that the sparking circuit is closed through the timer 21. This 50 has been fully demonstrated in practice. These rapidly produced succession of sparks establish what is approximately a continuous electrical flame and thus insure good ignition of the explosive charge.

The electrical igniter above described is 55 extremely simple, of comparatively small cost, has no delicate parts that are likely to get out of order and in actual practice has been found completely satisfactory for the purposes had in view. Furthermore, it 60 makes possible the use of a low tension ignition current and I have found that two or three ordinary dry cells are sufficient to produce the igniting sparks.

What I claim is:

1. In an electric igniter for explosive engines, a metal plug having an electrode thereon, a bushing in said plug, an insulating sleeve between said plug and bushing, a rock shaft journaled in said bushing, an electrode on the inner end of said shaft co-operating with the electrode on the plug, a lateral arm on the outer end of said rock shaft, an electro-magnet having a movable armature co-operating with the lateral arm of said rock shaft, a bracket supporting said electro-magnet, said bracket having a foot resting on the upper face of the plug, and a nut on the bushing to lock the bracket to the plug. 65 70 75

2. In an electric igniter for explosive engines, a metal plug having an electrode thereon, a metallic bushing axially mounted in said plug, an insulating sleeve between said plug and bushing, a rock shaft journaled in said bushing, an electrode on the inner end of said rock shaft co-operating with the rock shaft on the plug, a lateral arm on the outer end of said rock shaft, an electro-magnet having a movable armature co-operating with the lateral arm of said rock shaft, a bracket supporting said electro-magnet, said bracket having a foot resting on the upper face of the plug and surrounding the end of the bushing and a nut on the bushing to lock the bracket to the plug. 80 85 90 95

3. In an electric igniter for explosive engines, a metallic plug having a fixed and a movable electrode, a bracket fixed to said plug, an electro-magnet carried by said bracket and having an armature co-operating with said movable electrode, a casing mounted on said plug and inclosing said magnet, and a terminal screw on the bracket adapted to lock the casing on the plug and connect the electro-magnet with one side of the electric circuit. 100 105

4. In an electric igniter for explosive engines, a metallic plug having a fixed and a movable electrode, a bracket fixed to said plug, an electro-magnet carried by said bracket and having an armature co-operating with said movable electrode, a casing comprising a cylindrical body and a cap piece, mounted on said bracket and inclosing said magnet, a circuit terminal screw on the 110 bracket passing through the cap, and a nut on said screw serving to connect a circuit wire to said screw and lock the casing to the plug. 115

In testimony whereof I affix my signature 120 in presence of two witnesses.

EMIL WESTMAN.
